UNITED STATES PATENT OFFICE

91,623

DESIGN FOR A CASSEROLE, BOWL, OR SIMILAR ARTICLE

Louis E. Hellmann, Great Neck, N. Y., assignor to Continental Ceramics Corporation, New York, N. Y., a corporation of New York

Application September 22, 1933, Serial No. 49,313

Term of patent 7 years

To all whom it may concern:

Be it known that I, LOUIS E. HELLMANN, a citizen of the United States, residing in Great Neck, L. I., county of Nassau, and State of New York, have invented a new, original, and ornamental design for a Casserole, Bowl, or Similar Article, of which the following is a specification, reference being had to the accompanying drawing, forming a part thereof.

Fig. 1 is a top plan view of a casserole or bowl showing my new design; Fig. 2 is a side elevation of the casserole or bowl shown in Fig. 1, and Fig. 3 is a perspective view of the same casserole or bowl.

I claim:

The ornamental design for a casserole, bowl, or similar article as shown.

LOUIS E. HELLMANN.
